JOHN R. GILDA, OF ALBANY, NEW YORK.

BOTTOM DOUBLE SEAMER.

Application filed January 31, 1925. Serial No. 6,058.

My invention relates to machines for attaching the heads, tops or bottoms, to can bodies by means of a double seaming operation. The object of this invention is to produce an improved machine in which the can bodies and heads will be automatically delivered to the seaming mechanism, the double seaming operation completed and the work discharged from the machine; and the production from which will be much greater than is feasible from present types of machines adapted to perform the same work.

The manner in which I accomplish my object is illustrated in the accompanying drawings, which are in a certain sense illustrative only in that they show but one embodiment of my invention. In these drawings, Fig. 1 is a front elevation of a bottom double seaming machine, partly in section. Fig. 2 is a left end elevation. Fig. 3 is a right end elevation. Fig. 4 is a cross section along the line X—X on Fig. 1, looking in the direction indicated by the darts. Fig. 5 is a cross section along the same line but looking in opposite direction. Figs. 6 and 7 are details of the seaming rolls and the slides on which they are mounted. Fig. 8 is a perspective view of one of the sleeves forming a part of the head feeding mechanism.

The same reference characters refer to the same parts throughout the several views.

The drawings show a simple form of my invention, a machine which is adapted to double seam in but one head of a cylindrical can. This machine comprises a base or table 2, supported on leg members 3, in which is journaled a driving shaft 4, which may be driven from or by a pulley 5, or in any other suitable manner. Journaled in the base or table 2, is a counter-shaft 6, driven from the shaft 4 by means of the spur gears 7 and 8.

Supported by the table 2, are end brackets 9 and 10, in which is journaled a shaft 11, driven through a chain of spur gears 12, 13, 14, and 15, from the counter-shaft 6.

Fastened on the shaft 11, so as to rotate therewith is a hub member 16, in or on which are mounted a series of radially and circumferentially spaced rotatable shafts or spindles 17, one end of each having formed thereon or attached thereto, a mandrel 18 adapted to engage the work and to coact with the seaming rollers 19 to form the

seam. The seaming rollers 19, are mounted on carriers 20, slidably mounted in or on the member 16. The rollers 19 are preferably run on suitable roller bearings and are so attached to the sides to be readily detachable for replacement.

Each of the carriers 20, is provided with a stud 22^A or 22^B, on which is a cam engaging roller 23^A, or 23^B, adapted to engage in cam grooves formed in the cam plate 25, these cam grooves being adapted to actuate the slides 20, so as to advance the rollers into operative contact with the work, hold them in contact for the required period of time, then retract them to starting position, all at the proper times.

Loosely mounted on the shaft 11, and so connected together that they rotate as a unit, is a pair of gears 26^R, and 27^R, which are driven through an idler gear 28^R, by a spur gear 29^R, fastened on the counter shaft 6. Each of the spindles 17 has a pinion 30, fastened on the rear end thereof and all of these pinions are in mesh with the gear 27^R so that rotation of said gear will cause counter rotation of the pinions and the spindles to which they are attached.

Also mounted on the shaft 11, so as to be rotated therewith, is a hub member 31, in or on which is slidably mounted a series of radially and circumferentially spaced bearing sleeves 32, journaled in which are shafts or spindles 33, on the forward ends of which are formed, or fastened, work-engaging discs or members 34. The spindles 33 are concentric with the spindles 17 mounted in the member 16, and are driven by means of pinions 30^L meshing with the gear wheel 27^L driven through the gears 26^L, 28^L, and 29^L, from the counter shaft 6. The speed and direction of rotation of each concentric pair of spindles are to be identical, but the means for imparting rotation thereto may be different from that shown and described.

The bearings 32, slidable in the member 31, are adapted to be advanced and retreated at proper times by means of the plungers 39, attached thereto and which are provided with cam engaging rollers 38, adapted to engage the cam groove 36 formed in the cam ring 37. Force to drive forward the bearings 32, is applied or transmitted through a spring 40, thus providing a possible yielding which will care for variations in the cam lengths due to the progress of the seaming operation, or other likely variations, and so

insure the needful firm grip on the work at all times when the same is being acted upon by the rollers.

While no great amount of adjustments in the relative positions of the mechanism described in the paragraphs immediately preceding, and that described in the three paragraphs which immediately precede those, is possible in the machine illustrated, it is of course obvious that one or both of these groups of mechanism could be mounted on a sub base so that the relative position of one in relation to the other could be readily adjusted, thus making one machine capable of handling cans of different lengths. It is also obvious that the hub members 16 and 31 could be combined or made as a unit when the machine is required to handle but one length of can. It is also obvious that where two hub members are used, the recessed parts thereof (in which are the work receiving recesses 160 and 310) may be made removable so that they may be replaced by parts adapted to receive cans of a different diameter. The work-engaging parts would of course have to be changed to correspond, as would also the bottom feeding mechanism.

All of the spindles, 17 and 33, are preferably mounted in suitable roller bearings, but as this is standard practice they have not been shown in the drawings.

The position of the cam-engaging rollers 23^a and 23^b, in relation to the seaming rollers 19, must be adjustable if the machine is to handle cans of different diameters, and they are preferably adjustable to some extent on all machines of this type. In the machine illustrated this adjustment is provided for as illustrated in Fig. 6. The slide 20 is slotted through into the opening adapted to receive the base portions of the studs 22^a and 22^b, and a longitudinal rod 70, in the side of which is a notch 70^a, is inserted as illustrated. The roller bearing portions 22^a and 22^b, of the studs 22^a and 22^b are formed eccentric with the base portion so that rotation of the stud will vary the location of the cam rollers. The notch 70^a is adapted to pass the seaming roller studs 19^s, so that when the nut on the upper end of the rod 70 is tightened, both the studs 19^s and the stud 22^a (or 22^b) will be firmly clamped in adjusted positions.

Mounted in front of the member 16, or if but a single hub member is used that end thereof which carries the mandrels and seaming rollers, is a trough like structure adapted to receive the initially formed heads (tops or bottoms) to be fed into the work engaging mechanism by the automatic head feeding mechanism. This trough is here illustrated as comprising a bracket-like member 41, through which is an opening 420 adapted to pass the heads, which are

forced toward this opening in a manner which will be hereinafter described, and a number of rods 41^a, 41^b, 41^c, 41^d, and 41^e, the opposite ends of which are supported by a bracket arm 42, from a convenient part 70 of the frame of the machine.

Slidable respectively on the rods 41^a and 41^b, are the sleeves 43^A and 43^B, each of which is provided with a wing 43^w adapted to be brought into contact with the back of a pack of heads so as to hold them in a vertical position in the feeding trough. Each of these sleeves is also provided with a handle whereby it may be readily grasped by the operator so as to position it when desired, and each is fastened to a cable 47, to which is attached a weight 46, normally drawing said sleeve, and the pack of heads if the wing be in contact therewith, toward the feed opening 420. Each of these sleeves is also provided with a projection 43^p, which may be turned in behind a hook 44 on the bracket arm 42, so as to hold the sleeve at that end of the trough.

A feeding dial 48, lies closely against the face of the bracket 41, and is provided with hook like recesses 48^R, and is adapted to remove bottoms one at a time from the pack 56 in the feeding trough and to deliver them in front of the mandrels 18. The feeding dial is provided with a cover plate (not shown) which prevents the bottoms from escaping from the feeding mechanism until they are picked out by the mandrels 18.

Can bodies are delivered to the machine by gravity, coming down a slide as indicated at 53, and dropping into the recesses in the members 16 and 31. After the completion of the double seaming operation the cans drop out into a chute or slide as indicated at 55 in Figs. 2 and 4.

The operation of my improved double seaming machine is as follows: When the machine is in operation bottoms are removed one at a time from the pack 56 and delivered into the recesses in the members 16 and in front of the mandrels 18, which engage with the bottoms and carry them out of the feeding mechanism, but just prior to the completion of this operation a can body drops into the recess and in front of the bottom. At this time the cam groove 36 will actuate the plunger 39, and force forward the sleeve 32 and the member 34 until the can body and the bottom are firmly gripped between the mandrel 18 and the member 34 so as to be rotated therewith. The cam grooves 24 A and B then force in the slides 20, and the rollers 19 carried thereon perform the double seaming operation in the usual manner. These seaming rollers are held in working position until just before the work reaches the lower point in the arc of its travel when the cam groove will retract the sleeve 32 and permit the

work to drop out onto the chute or slide 55. Should the work be inclined to cling to the mandrels, the spring actuated kick-outs 21, which are pressed back by the forward grip-

5 ping movement of the sleeves 32 and the parts 34, will force it free. I prefer, however, to use a suitable positive wedge device, indicated by 54 on Fig. 4, which is adapted to wedge the work off the man-

10 drills should the kick-outs fail to do so.

In my improved machine above described, and illustrated by the drawings, the work is continuously acted upon by the seaming rollers during most of the time that it is 15 travelling from the entry point to the point at which it is expelled from the machine; and when the machine is being operated at a speed which will seam in the heads of a given number of cans per minute, the man- 20 drills and seaming rollers need to revolve at a speed equal to only about one-quarter the speed of those parts on present machines having an equal rate of production, and this comparatively slow speed insures 25 a longer life to those parts which are customarily renewed at intervals.

I claim:

1. In a double seaming machine, the combination of a supporting frame; a rotatable 30 unit comprising a hub member on a shaft, and having a series of circumferentially spaced pockets in each of which is an opposed pair of work-engaging members secured to adjacent ends of a pair of rotatable spindles one of which is journaled in a longitudinally slidable sleeve provided with means operatively connecting it with a stationary cam ring, means whereby rotation of the unit will cause positive axial 35 rotation of all of said spindles, and pairs of seaming rollers above, and radially in line with, each of said pockets, each roller mounted on a carrier slidable radially on said hub member and provided with means operatively connecting it with a second cam 40 ring; means for rotating said unit; a stationary cam ring adapted to successively actuate said slidable sleeves to advance and withdraw them as the unit rotates; a second stationary cam ring adapted to suc- 45 cessively actuate said carriers to advance and withdraw them as the unit rotates; means for introducing can bodies and can heads into said pockets in proper relative 50 positions to be engaged by said work-engaging members; and means for expelling the finished work from the unit.

2. In a double seaming machine, the combination of a supporting frame; a rotatable 55 unit comprising a hub member on a shaft, and having a series of circumferentially spaced pockets in each of which is an opposed pair of work-engaging members secured to adjacent ends of a pair of rotatable spindles one of which is journaled in a longitudinally slidable sleeve provided with means operatively connecting it with a stationary cam ring, means whereby the rotation of the unit will cause positive axial 60 rotation of all of said spindles, and pairs of seaming rollers above, and radially in line with, each of said pockets, each roller mounted on a carrier slidable radially on said hub member and provided with means operatively connecting it with a second cam 65 ring; means for rotating said unit; a sta-

of seaming rollers above, and radially in line with, each of said pockets, each roller mounted on a carrier slidable radially on said hub member and provided with means operatively connecting it with a second cam 70 ring; means for rotating said unit; a stationary cam ring adapted to successively actuate said slidable sleeves to advance and withdraw them as the unit rotates; a second stationary cam ring adapted to suc- 75 cessively actuate said carriers to advance and withdraw them as the unit rotates; and means for introducing can bodies and can heads into said pockets in proper relative 80 positions to be engaged by said work-engaging members.

3. In a double seaming machine, the combination of a supporting frame; a rotatable 85 unit comprising a hub member on a shaft, and having a series of circumferentially spaced pockets in each of which is an opposed pair of work-engaging members secured to adjacent ends of a pair of rotatable spindles one of which is journaled in a longitudinally slidable sleeve provided with means operatively connecting it with a stationary cam ring, means whereby the rotation of the unit will cause positive axial 90 rotation of all of said spindles, and pairs of seaming rollers above, and radially in line with, each of said pockets, each roller mounted on a carrier slidable radially on said hub member and provided with means operatively connecting it with a second cam 95 ring; means for rotating said unit; a stationary cam ring adapted to successively actuate said slidable sleeves to advance and withdraw them as the unit rotates; a second stationary cam ring adapted to suc- 100 cessively actuate said carriers to advance and withdraw them as the unit rotates; means for introducing can bodies and can heads into said pockets in proper relative 105 positions to be engaged by said work-engaging members; and means for expelling the finished work from the unit.

4. In a double seaming machine, the combination of a supporting frame; a rotatable 110 unit comprising a hub member on a shaft, and having a series of circumferentially spaced pockets in each of which is an opposed pair of work-engaging members secured to adjacent ends of a pair of rotatable spindles one of which is journaled in a longitudinally slidable sleeve provided with means operatively connecting it with a stationary cam ring, means whereby the rotation of the unit will cause positive axial 115 rotation of all of said spindles, and pairs of seaming rollers above, and radially in line with, each of said pockets, each roller mounted on a carrier slidable radially on said hub member and provided with means operatively connecting it with a second cam 120 ring; means for rotating said unit; a sta-

tionary cam ring adapted to successively actuate said slidable sleeves to advance and withdraw them as the unit rotates; a second stationary cam ring adapted to successively actuate said carriers to advance and withdraw them as the unit rotates; means for introducing can bodies, by gravity into said pockets; a feed trough adapted to hold pre-formed can heads; and a rotating mechanism adapted to remove can heads, one by one, from said feed trough and deliver them to said pockets in juxtaposition to a work-engaging member.

5. In a work carrying, work engaging and driving unit for a double seaming machine, the combination of: a shaft; a hub member thereon having a series of circumferentially spaced pockets therein; in each of said pockets an opposed pair of work-engaging members secured to adjacent ends of a pair of rotatable spindles carried by said hub member, one of each of pairs of spindles journaled in a longitudinally slidable sleeve provided with means adapted to contact with a stationary part of the machine whereby said sleeve will be advanced and withdrawn as the unit is rotated; means whereby rotation of said unit will cause positive axial rotation of all of said spindles, and means whereby the unit may be caused to rotate; and pairs of seaming rollers above, and radially in line with, each of said pockets, each of said rollers mounted on a carrier slidable in ways on said hub member and provided with means adapted to contact with a stationary part of the machine whereby said carrier will be advanced and withdrawn as the unit is rotated.
6. In a work carrying, work engaging and driving unit for a double seaming machine, the combination of: a shaft, with a hub member thereon having a series of circumferentially spaced pockets therein; in each

45 pocket an opposed pair of work-engaging members secured to adjacent ends of a pair of rotatable spindles carried by said hub member and one of which is journaled in a longitudinally slidable sleeve provided with means adapted to operatively connect it with a stationary part of the machine whereby the rotation of the unit will cause the sleeve to be advanced and withdrawn, the other spindle of the pair provided with a spring actuated plunger the front end of which normally projects beyond the work-engaging member secured to said spindle; means whereby the rotation of said unit will cause positive axial rotation of all of said spindles, and means whereby the unit may be caused to rotate; and pairs of seaming rollers above, and radially in line with, each of said pockets, each of said rollers mounted on a carrier slidable in ways on said hub member and provided with means adapted to contact with a stationary part of the machine whereby said carrier will be advanced and withdrawn as the unit is rotated.

7. In a can head feeding device for a double seaming machine or the like, the combination of a trough adapted to receive a stack of pre-formed can heads and provided with a discharge opening at one end thereof; yielding means adapted to contact with a stack of heads placed in said trough and to force them toward and through said discharge opening; a rotatable disc with a series of recesses therein registering at each revolution of said disc with said discharge opening and adapted to receive therein a single can head and to deliver it, at another point in its revolution, to the work-engaging mechanism of the seaming machine; and means for causing rotation of said disc.

In testimony whereof I have affixed my signature.

JOHN R. GILDA.
